UNITED STATES PATENT OFFICE.

HENRY MOSBAUGHER, OF WILKINSBURG, PENNSYLVANIA.

PALM-REST FOR FIREARMS.

SPECIFICATION forming part of Letters Patent No. 703,964, dated July 1, 1902.

Application filed January 14, 1902. Serial No. 89,650. (No model.)

To all whom it may concern:

Be it known that I, HENRY MOSBAUGHER, a citizen of the United States of America, residing at Wilkinsburg, in the county of Allegheny and State of Pennsylvania, have invented certain new and useful Improvements in Adjustable Palm-Rests, of which the following is a specification, reference being had therein to the accompanying drawings.

10 This invention relates to certain new and useful improvements in adjustable palm-rests for guns, and is particularly adapted to be employed and secured to target-guns for target practice.

15 The present invention has for its object to provide a target-gun with an adjustable palm-rest that may be easily attached and removed from the lever or trigger guard.

Another object of the present invention is 20 to provide a device of the above-described character that will be extremely simple in construction, strong, durable, comparatively inexpensive to manufacture, and highly efficient in its use.

25 With the above and other objects in view the invention consists in the novel combination and arrangement of parts, to be herein-after more fully described, and specifically pointed out in the claims.

30 In describing the invention in detail reference is had to the accompanying drawings, forming a part of this specification, and wherein like numerals of reference indicate like parts throughout the several views, in which—

35 Figure 1 is a vertical sectional view of my improved adjustable palm-rest, showing the same applied in position to a gun, the latter being illustrated in dotted lines. Fig. 2 is a transverse vertical sectional view of the same.

40 Fig. 3 is a perspective view showing the invention in use.

In the drawings, the reference-numeral 1 indicates the gun, and 2 the trigger. The numeral 3 represents the lever or trigger guard. Upon this trigger-guard is secured the palm-rest, which consists of a spherical body portion 4, having formed therein a central opening 5, extending a considerable distance into the body portion 4. In this opening 5 is secured a cylindrical casing 6, extending upwardly a distance above the body

portion 4. Said cylindrical casing 6 carries an annular inwardly-extending shoulder 7 and has formed in the base a screw-threaded opening 8 to receive the screw-threaded shank 9, and the clamping members 10 11 represent a recess formed in the base of the body portion 4 for the reception of the threaded stem 9.

The manner of applying my improved device is as follows: The body portion 4, to which the cylindrical casing 6 is secured, is revolved to allow the clamping members to extend beyond the casing, as shown in full lines in Fig. 2 of the drawings. The lower portion of the trigger-guard is then secured endwise into the opening between the clamping members, and the gun is then turned in proper position and the spherical body portion 6 revolved to the position as shown in Fig. 2, thereby clamping the lever or trigger guard into the jaws of the palm-rest.

The spherical body by reason of its shape forms a most convenient and easy rest to hold within the palm of the hand and affords a steady support for the gun during the aiming and firing of the same. The body being movably mounted on the trigger-guard permits of the former occupying any desired position which may be found most convenient to the operator.

It will be seen that the device may be easily adjusted to any desired position. The many other advantages obtained by the use of my invention will be readily apparent from the foregoing description, taken in connection with the accompanying drawings.

It will be noted that various changes may be made in the details of construction without departing from the general spirit of my invention.

Having fully described my invention, what I claim as new, and desire to secure by Letters Patent, is—

1. In a palm-rest for guns and the like, the combination of a spherical body portion, a cylindrical casing secured in said body portion, a screw-threaded shank secured in said casing, and clamping members formed integral with said shank, substantially as described.

2. In a palm-rest for guns and the like, the combination of a spherical body portion having an opening formed therein, a cylindrical

casing secured in said opening having a
screw-threaded opening formed in the lower
portion thereof, a screw-threaded shank se-
cured in said screw-threaded openings, and
5 clamps carried by said shank, all parts being
arranged substantially as described and for
the purpose set forth.

in testimony whereof I affix my signature
in the presence of two witnesses.

HENRY MOSBAUGHER.

Witnesses:

JOHN NOLAND,
E. E. POTTER.
